UNITED STATES PATENT OFFICE

JERVIS B. WEBB, OF DETROIT, MICHIGAN

OVERHEAD CONVEYER

Application filed October 17, 1928. Serial No. 312,951.

The present invention relates to overhead conveyors and particularly to track construction therefor.

Among the objects of the invention is to provide novel means for connecting abutting ends of track rail sections.

Another object is connecting means so constructed and arranged as to also form a particularly efficient hanger attaching means.

Other objects will readily occur to those skilled in the art upon reference to the following description and the accompanying drawing, in which

Fig. 1 is an end elevation of the device.

Fig. 2 is a side elevation thereof.

Fig. 3 is a top plan view, and

Fig. 4 is an enlarged section on line 4—4 of Fig. 3.

As indicated in the drawings the device comprises a pair of identical plates each having a vertical web 10 and a horizontal web 20 disposed at the lower edge of the vertical web. The web 10 is provided with suitable openings for the passage of bolts 11 and at one end near the top edge with a short longitudinal rib 12 on the face opposite the webs 20.

The webs 20 are preferably not coextensive with web 10 but extend toward each other from the ends of web 10 for a distance equal to about the length of a rib 12. These webs 20 are turned downwardly and backwardly at an angle as at 21, so that a section through this edge shows a hook-like formation, and within the hook 23 the metal is formed so that small low ribs 22 extend across the hook, two or more of such ribs 22 being preferably provided.

As indicated in Figs. 1 and 2 a pair of the plates is used to grip the upper flanges 30 of an I-beam 31 forming the conveyor track and preferably arranged to grip abutting ends 31^a and 31^b of adjacent sections of said track.

The device may be sufficiently rigid to be used only for the purpose of such connections but is also intended for use as a track hanger, the bolts 11, beside acting as clamping means, also serving to secure the assembly to angle irons or other suitable bracket members such as are diagrammatically shown in Figs. 1 and 2.

In applying the device to a track, the ribs 12 act as fulcrums and cause the hooks 23 to be drawn toward each other by the bolts 11, sufficient pressure being exerted to cause the small ribs 22 to enter the edges of the I-beam flange and thereby prevent relative longitudinal movement of the I-beam and hook.

Now having described the invention and the preferred form of embodiment thereof, it is to be understood that the said invention is to be limited, not to the specific details herein set forth but only by the scope of the claims which follow.

What I claim is:—

1. A connecting device for conveyor tracks comprising a pair of plates each having a horizontally extending hooked portion and a vertically extending portion provided with a fulcrum, and means located between said hooked portion and fulcrum for drawing said plates together.

2. A connecting device for conveyor tracks comprising a pair of plates each having a horizontally extending hooked portion and a vertically extending perforated web with a rib above said perforations and extending in a direction opposite to that of the hooked portion, and means for drawing said plates together.

3. A connecting device for conveyor tracks comprising a pair of plates each having horizontally extending webs the extreme edges of which are turned down and backwardly at an angle to form a hook, and a vertical web provided at one end with a rib located on the face opposite said first web, and clamping means between said rib and said first web.

4. A connecting device for conveyor tracks comprising a pair of plates each having horizontally extending webs the extreme edges of which are turned down and backwardly at an angle to form a hook, and a vertical web provided at one end with a rib located on the face opposite said first web, and clamping means between said rib and said first web, there being short ribs within and extending across said hooks.

5. A connecting device for conveyor tracks comprising a pair of plates each having a

horizontally extending hooked portion and a vertically extending portion provided with a fulcrum, and means located between said hooked portion and fulcrum for drawing said plates together, means being provided to prevent relative longitudinal movement between said device and said tracks.
